UNITED STATES PATENT OFFICE.

RUDOLF SINKWITZ, OF COPITZ, GERMANY, ASSIGNOR TO WILHELM KAUFMANN, OF DRESDEN-A, SAXONY, GERMANY.

DEVICE FOR THROWING, WASHING, AND REELING SPOOLED ARTIFICIAL SILK.

1,427,238.

Specification of Letters Patent. Patented Aug. 29, 1922.

Application filed January 30, 1922. Serial No. 532,830.

To all whom it may concern:

Be it known that I, RUDOLF SINKWITZ, a citizen of the German Republic, residing at Copitz, on the River Elbe, Germany, have 5 invented certain new and useful Improvements in a Device for Throwing, Washing, and Reeling Spooled Artificial Silk, of which the following is a specification.

This invention relates to devices for 10 throwing, washing and reeling artificial threads of cellulose which have been spooled after precipitation and it relates more specially to a device by which the operations mentioned can be executed in one continuous 15 course. The devices of this type of known construction suffer from the inconvenience that the freshly precipitated thread has very little resistance and that at the continuous course of work it is submitted to a considerable 20 tensile stress and to considerable vibrations as it has to travel over a long distance and over several pulleys and to traverse several baths. It is further not possible with the well known devices to guide the thread 25 by hand over the different guide pulleys and through the baths which is often necessary as the thread breaks frequently.

This invention has for its object in the first instance to obtain a complete coagulation 30 of the thread and at the same time an essential simplification of the washing process. These results are obtained by making the freshly precipitated thread, which in order to complete the coagulation is wound 35 usually upon a spool revolving in a top bath, run through a washing conduit in being pulled off the spool placed upon a twisting spindle, the thread being thrown along in said conduit by the current of the water and 40 being reeled directly when getting out of the washing conduit. The thread is thoroughly washed in this manner as the length of the washing conduit is not limited and the conduit can be of convenient curvature, 45 and the noxious tensile stress is considerably diminished as the thread floats in the washing liquid without tension. The curvature of the washing conduit has further the advantage that, notwithstanding the length of 50 the washing conduit, the reel can be arranged in close proximity to the twisting spindle so that both devices can be supervised simultaneously by one man.

The invention relates further to a device 55 for unwinding the thread from the twisting

spool and for the insertion of the same into the washing conduit, said device ensuring that the separation of the thread from the twisting spool and from the pulling off device is effected with as little resistance as 60 possible.

A further improvement relates to a moistening device for the artificial thread upon the twisting spool which is necessary as this thread dries rapidly and because brittle in 65 consequence of its being thrown about, wherefrom results that at the twisting from the spool considerable waste remains upon the spool.

According to the invention an elastic tensioning device is arranged ahead of the reel which yields, as soon as the thread stops, for instance if it sticks to the wall of the washing conduit, so that the thread is prevented from breaking as it must not be pulled by 75 the reel or only very little.

In order that the invention may be clearly understood, I shall proceed to describe the same with reference to the form of construction shown by way of example on 80 the accompanying drawings, wherein:—

Fig. 1 is a diagrammatic side elevation of a double device for the throwing, washing and reeling of an artificial thread.

Fig. 2 is a front view of Fig. 1 showing 85 the two companion devices partly merely indicated.

Figs. 3 and 4 are respectively a side elevation and front view on a larger scale showing the device for pulling the thread 90 off the twisting spool and for feeding the same into the washing conduit.

Figs. 5 and 6 are respectively a front elevation and perspective view of the tensioning device for the thread coming out of the 95 washing conduit.

Figs. 7 and 8 are respectively a side elevation and a cross section on line A—B of Fig. 7 showing the moistening device for the twisting spool.

Figs. 9 and 10 show respectively in section on line C—D of Fig. 10 and in front elevation the arrangement of a number of devices superposed and juxtaposed, the identical oppositely situated half being omitted. 105

The different devices are mounted upon a frame 1. Across the top of the frame 1 a water pipe 2 extends from which several tubes 5 branch off which have each a shutting off cock 3 and a nozzle shaped free end 110

4. The nozzle 4 is directed upon the inlet opening 6 of a washing conduit 7 which is bent repeatedly in U-shape and terminates at the same side at which the inlet orifice 6 is situated. The end 8 of the washing conduit is situated above a gutter 9 mounted upon a bracket 10. Upon a bracket 11 fixed to the frame 1 a number of receptacles 12 are arranged the one at the side of the other, each 10 of which comprises a revoluble twisting spindle 13, the spool 14 of which is situated in said receptacle. Under the bottom plate of receptacle 12 a string pulley 22 is fixed upon the projecting lower end of the twisting spindle 13. The driving string, not shown, is bent around this string pulley.

From the water pipe 2 vertical tubes 16 are branched off, each of which has a stop valve 15. Each tube 16 is closed at the lower end 20 and presents a hole 18 at the same height as the middle of the spool. The lower end of the tube 16 is enclosed in an envelope 17 which is arranged eccentrically with regard to the tube 16 so that the hole 18 stands at a 25 certain distance from the wall of said envelope 17. The envelope 17 has opposite the spool a narrow slit 19 the length of which corresponds with the height of the spool. One edge of the slit is bevelled so that the 30 edge 20 of the same is situated upon the inner surface of the envelope. The hole 18 of tube 16 stands opposite the edge 20 of the slit 19. In the bottom plate of the envelope 17 a small hole 21 is provided for the out- 35 flow of the water in excess. The water which comes in contact with the edge of the slit 19 will be atomized already at a low pressure so that it moistens in this state the spool 14 upon its entire height, the thread being thus 40 kept constantly moist so that it can be twisted off from the beginning to the end.

A thread guide 23 and a brake fork 24 are arranged above the twisting spindle 13 designed to brake the thread pulled off the 45 spool 14 more or less according to their adjustment. The pulling-off device arranged above the brake consists of a roller 25 (Figs. 3 and 4) which has ribs 26 and of a grooved roller 27 preferably made from glazed porcelain. Two rollers 26 are always mounted upon one axle 28 and two rollers 27 are mounted upon an axle 29. The rollers 27 revolve with a greater circumferential speed than the rollers 26.

50 The thread coming from the twisting spool 14 and guided by the thread guide 23 and the brake 24 is wound around the pulling-off roller 25 and then around the roller 27 from which it is thrown into the orifice 6 of the washing conduit 7. The connection of the pulling-off roller 25 with the tensioning roller 27 has the advantage that the pulling off device requires little space, a diameter of about 50 mm. being sufficient for the pulling-off roller 25 whilst hitherto this roller

had a diameter of approximately 300 to 400 mm.; a diameter of approximately 20 mm. is sufficient for the roller 27.

At the outlet end of the washing conduit 7 upon the gutter 9 for the washing liquid a 70 device for tensioning the thread and for compensating retardations in the movement of the thread is arranged in front of the reel. This device consists of a U-shaped bow 30 of glass with cranked arms which are mounted 75 in two bearing forks 31 which are preferably made also of glass rods. Each bearing fork 31 is mounted with its shaft in a support 32 fixed upon the gutter 9. Angles or hooks 33 are further provided in the supports 32 one 80 arm of each angle being pivotally mounted in the corresponding support and the other arm of the same gripping over the middle part of the arm of the crank bow 30 which is thus prevented from getting out of the bearing forks. The bow 30 can be released for removal by turning the angles or hooks 33. The ends of the arms of the bow 30 are so heavy that the bow adopts a vertical position under the action of its own weight. 90

The thread coming from the washing conduit is guided at an angle over the bow 30 and wound around the reel 34. As soon as a stoppage occurs the thread is stretched and forces the bow 30 to adopt an inclined position. As soon as the thread gets slack again the bow returns to the vertical position. 95

The devices described can be arranged in any required number, the one at the side of the other and the one above the other or opposite each other. In the arrangement shown on Figs. 9 and 10 two superposed rows of twisting spindles and of pulling-off devices with corresponding washing conduit and a common gutter are superposed, only 100 one row of reels and tensioning devices being provided. The washing conduits can be made as long as necessary by bending the same repeatedly. If the devices are arranged at both sides of the frame the washing conduits are situated at the middle between the two sets of devices partly superposed and partly juxtaposed. 105

I claim:—

1. An improved device for throwing, 115 washing and reeling spooled artificial silk comprising in combination a twisting spindle, a spool upon said spindle upon which the artificial thread is wound, a long washing conduit through which the thread is assisted, 120 on being drawn therethrough, by the flow of the washing liquid, so as to relieve tension on the thread, means for guiding the thread from the spool to the inlet orifice of said washing conduit, and a reel at the end of 125 said washing conduit upon which the thread is wound.

2. An improved device for throwing, 130 washing and reeling spooled artificial silk comprising in combination a twisting spin-

dle, a spool upon said spindle upon which the artificial thread is wound, a long washing conduit through which the thread is assisted, in being drawn therethrough, by the flow of 5 the washing liquid, so as to relieve tension on the thread, said conduit being curved so that its outlet end is situated at the same side as the inlet end, means for guiding the thread for the spool to the inlet orifice of 10 said washing conduit, and a reel at the end of said washing conduit upon which the thread is wound.

3. An improved device for throwing, washing and reeling spooled artificial silk 15 comprising in combination a twisting spindle, a spool upon said spindle upon which the artificial thread is wound, a long washing conduit through which the thread is assisted, in being drawn therethrough by the flow of 20 the washing liquid so as to relieve tension on the thread, said conduit being curved so that its outlet end is situated at the same side as the inlet end, a revolving pulling-off roller for unwinding the thread from the spool, a 25 doffing roller revolving at higher speed than said pulling-off roller for taking the thread from the pulling-off roller and conducting the thread into the inlet orifice of the washing conduit, and a reel at the end of said 30 washing conduit upon which the thread is wound.

4. An improved device for throwing, washing and reeling spooled artificial silk

comprising in combination a twisting spindle, a spool upon said spindle upon which 35 the artificial thread is wound, a water atomizer arranged opposite said spool for moistening the spool during the twisting process, a long washing conduit through which the thread is assisted, in being drawn therethrough by the flow of the washing liquid so 40 as to relieve tension on the thread, means for guiding the thread from the spool to the inlet orifice of said washing conduit, and a reel at the end of said washing conduit 45 upon which the thread is wound.

5. An improved device for throwing, washing and reeling spooled artificial silk comprising in combination a twisting spindle, a spool upon said spindle upon which 50 the artificial thread is wound, a long washing conduit through which the thread is assisted in being drawn therethrough by the flow of the washing liquid so as to relieve 55 tension on the thread, means for guiding the thread from the spool to the inlet orifice of said washing conduit, and a reel at the end of said washing conduit upon which the thread is wound, and a tensioning device between the outlet end of the washing conduit 60 and the reel consisting of an oscillating bow of glass which is held in the tensioning position by the action of its own weight.

In testimony whereof I affix my signature.

RUDOLF SINKWITZ.
